Application June 22, 1937, Serial No. 149,612

8 Claims. (Cl. 93—8)

5 My invention relates to an apparatus and method for applying relatively small sections of flat material to a series of objects and more specifically relates to an apparatus and method for applying reinforcing patches of paper onto the bottom of paper bags.

10 The bag operated upon by my invention comprises the ordinary folded paper bag produced from paper which is cut and folded in tubular shape, secured in such tubular form, and a bottom formed thereon by folding one end of the tube in such a way as to close the end. According to my invention I automatically apply over the folded flaps of such a paper bag a reinforcing 15 patch designed to hold the flaps securely in place, to reinforce the bottom of the bag against a load thereon (the bottom of the bag ordinarily representing its weakest point), and also to make the bag sift-proof i. e. to prevent powdered material contained therein from sifting through.

20 It has been customary in this art to apply the re-enforcing patches to the bottom of the bag by hand, commercially satisfactory machines having been unavailable. In hand operation, superfluous operations are necessitated by practical circumstance. When the worker picks up a patch and applies adhesive to it and repeats this operation rapidly he is bound to smear adhesive on his fingers and from there to both sides of subsequently handled patches. After the adhesive smeared patch is applied to the bag, the bag is stored with other bags. If adhesive is smeared on both sides of the patch, the bag adheres to adjacent bags. An extra operation of either 25 cleaning the patch or separating the sticky bags is therefore necessary. This materially increases the cost of the operation. Hand operation is therefore highly undesirable.

30 It has long been desired to replace the usual method of hand application of such small reinforcing patches to bags, but it has been found difficult to discover a machine adapted to perform the necessary operations with the requisite speed, accuracy and without frequent tie-ups. 35 Although the operation is a uniform one, it has been found difficult to make an economically feasible machine to perform the work. The present machine of my invention can operate on bags delivered automatically or by hand.

40 An object of my invention is to provide a novel method for applying re-enforcing patches to paper bags.

45 Another object of my invention is to provide a novel apparatus for applying said re-enforcing sections to paper bags.

5 Another object of my invention is to provide synchronous means for turning the folded bottom of a paper bag to an angle with the remainder of the bag and pushing said turned bottom forward after a patch is applied thereto.

5 Another object of my invention is to provide a means for varying the extent of an intermittent feeding device.

10 Another object of my invention is to provide novel means for continuously drawing forward an adhesive surface strip.

15 Another object of my invention is to provide synchronous means for performing a series of operations.

20 Another object of my invention is to utilize the lower blade of the cutting knives as a positioning stop for the paper bag to which the cut patch is applied.

25 Other objects will be evident as I proceed to more fully describe my invention.

Briefly, I apply a re-enforcing patch to the bottom of a paper bag by causing a strip of material from which such patches are to be cut to be brought forward between suitable feeding rollers and over an adhesion inducing means, which is adapted to apply an adhesion inducing surface onto the underside of this strip of reinforcing material, and I then lead this adhesive strip forward to a position wherein it lies directly over the bag, the bag having been brought forward either automatically or by hand from a bag making machine at the other end of this patch applying machine to a position where its forward bottom portion lies against the lower blade of the cutting knife and under the reinforcing strip with the folded bottom portion of the bag facing upwardly and the moistened adhesive portion of the reinforcing strip facing downwardly. Thereupon, the patch is cut off from the reinforcing strip and applied to the folded bottom of the bag. The folded portion of the bag with the patch applied thereon is then turned at an angle along the axis of the bottom of the bag so that another means can be introduced to push the rear end of the folded bottom portion forward and introduce it between two coacting belts that carry it away into a receptacle.

30 Figure 1 represents a plan view of the apparatus of my invention.

35 Figure 2 is a cross-section taken along the line 2—2 of Figure 1.

40 Figure 3 is a side elevation taken along the line 3—3 of Figure 1.

45 Figure 4 represents a side elevation of the cut-

50 55

ting means of this invention taken along the line 4—4 of Figure 2.

Figure 5 represents a side elevation taken along the line 5—5 of Figure 1.

5 Figure 6 represents a plan view of the cam and cam mountings taken along the line 6—6 of Figure 2.

10 Figure 7 is a side elevatiton of the pawl and ratchet arrangement by which the intermittent feeding operation is obtained taken along the line 7—7 of Figure 1.

15 Figures 8, 9, 10 and 11 are cross-sectional side elevations showing the operations of bringing the bag forward to its proper position under the manipulating member and against the lower knife for cutting a reinforcing patch, applying the patch to the bottom of a paper bag, pressing the applied reinforcing means to the bottom of the bag, turning the bottom of the bag to an 20 angle with respect to the bag, and discharging the bag from the working platform.

Figure 12 represents a plan view of the bag.

Figure 13 represents a side elevation of the bottom of the bag.

25 Referring now more particularly to the drawings, and especially to Figure 2, I provide upon a suitable structure 1 a supporting arm 2 secured by the bolts 2'. Upon this supporting arm is mounted a reel 3 adapted to carry a roll of reinforcing paper 4 with an adhesive under-surface 5. The paper 4 is led forward between rubber rolls 8 and 9 fixedly mounted on shafts 6 and 7 respectively, said rubber rolls being adapted to coat and feed forward the paper 4. These rolls are 30 operated intermittently by means shown in Figure 5 and which will be more specifically described later. Roll 8 is yieldably pressed toward roll 9 by a spring 11 which acts to draw roll 8 towards roll 9, the shaft 6 upon which roll 8 35 is mounted being set upon an arm 12 pivoted at 13.

After passing between rolls 8 and 9 the paper 4 then travels over an applicator drum 16 fixedly mounted on shaft 15 driven by chain 17 as will be more specifically described hereafter. The applicator drum 16 is positioned to move through the tank 19 which tank carries adhesion-inducing liquid 20. From the applicator 16, the paper 4 is fed over a flanged roller 23 mounted upon 45 a shaft 22, also driven by chain 17 and adapted to coat with a laterally equal flanged roll 24 mounted on shaft 26 which is freely movable in 50 sliding vertical relation in slot 27.

Set in horizontal alignment and to be seen in 55 Figures 2 and 4 is a lower knife blade 29 adapted to coat with and pivoted at 28 to an upper knife blade 30 mounted on an arm 31, which arm 31 is pivotally mounted at 32 and is moved vertically against the action of the spring 33 by a 60 cam 161 against a roller 162 mounted on an arm 163 pivoted at 164, which cam will be more specifically described hereafter.

65 The apparatus above described in detail operates to bring forward the reinforcing strip 4 with its adhesive coated undersurface 5 between the rolls 8 and 9, which intermittently operate to feed forward this strip over the adhesion inducing means 16, whereupon the reinforcing strip 4 is brought forward between the flanged rolls 70 23 and 24, which operate to hold the strip only at its edges and exert a constant pressure to drag it forward. The strip is thus led forward between the knives 29 and 30 to a position under the manipulating member 70 and over the bag, the introduction of which will be described. The

knives 29 and 30 then operate to cut off the small patch, which is to be applied to the bottom of the paper bag.

On a suitable supporting structure is mounted a platform 50 on which the bags to be reinforced are brought from the bag making machine either automatically or by hand. A section of the platform 50 is cut away at 51 through which protrudes a pusher rod 52 adapted to push forward the bags to the position in which the reinforcement patch will be applied. The rod 52 is firmly affixed at 55 to an arm 56. The arm 56 is rigidly connected through the pivot 57 to the arm 58 which terminates in a roller 59 forced to bear against the cam 166 by the action of a spring 15 60. The cam 166 thus controls the operation of the pusher rod 52. The pusher rod 52 operates to move forward the bag to be operated on so that its folded bottom lies under the manipulating member 70 which is shown in more detail 20 in Figures 8 to 11. The lower knife 29 acts as a stop and positioning means for the forward part of the bottom of bag. See Figures 2 and 8. This is an important feature of my invention.

Adapted to coat with said manipulating mem- 25 ber 70 is a trigger 75 mounted on a shaft 76 and actuated by vertically moving rod 77 pivoted at 78 and 79 and terminating in said pivot 79 resting in a roller 81 which rides on a cam 158 whose action will be more fully described here- 30 after. Said vertically moving rod 77 is connected with an arm 82 through a pivot 79, the arm 82 being fixedly pivoted at 83. The vertical motion of the rod 77 acts against the spring 84.

Two traveling belts 87 and 88 are trained over 35 fixed rollers 89, 91, 92, 93, 95 and 96 and roll 95 terminates in a sprocket wheel 173 which is driven by a chain 172 as shown in Figure 3. The lower portion of the belt 88 is trained over a roll 97 mounted on a shaft 98 in an arm 99, 40 which arm is pivoted at 100. The arm 99 is acted on by spring 102 so that the roll 97 tends to pull the belt 88 downwardly and maintain it in a taut condition, thus maintaining a pressure between the belts during their contacting path from roll- 45 ers 92 and 93 to rollers 95 and 96.

The chain 17 moves to drive the applicator 16 and the flanged roll 23 by means of the pulley 110 mounted upon the power driven shaft 155. The coacting belts 87 and 88 deliver the pressed 50 bag and reinforcing piece into the receptacle 112.

The above described apparatus serves to bring forward the bag, which has been delivered automatically or by hand from the bag making machine A and is pushed forward by the rod 52 with its folded bottom portion 201 uppermost as shown in Figure 13, to a position in which the bottom portion lies directly under the manipulating member 70, whereupon the patch 202 with the adhesive surface drops on the upper folded 60 portion of the bottom of the bag 200 forming a reinforcing patch thereon. The manipulating member 70 then swings in a clockwise movement, causing the bottom of the bag to be turned upwardly as in Figure 10 so that when the trigger 65 75 enters between the bifurcations 186 and 187 of the manipulating member 70, the bottom of the bag is both pressed by the manipulating member 70 and pushed forward into engagement with the coacting belts 87 and 88 wherein the 70 reinforcing patch 202 is firmly pressed into permanent engagement with the bottom of the bag 201 and the bag 200 is conducted forward into the receptacle 112.

Referring more particularly to Figure 5, at the 75

end of the shaft 7 on which is mounted the feeder roll 9 is a sprocket wheel 113, over which is trained a chain 114 which moves in a path indicated by the arrow over the ratchet wheel 115 and 5 in engagement therewith. This ratchet wheel 115 with teeth 116 is suitably mounted on the shaft 117, to the end of which shaft is affixed arm 118, the end of which is in pivot engagement at the point 119 with an arm 120. At this pivot 10 point 119 is a pawl 121 which engages the ratchet teeth 116, as shown in more detail in Figure 7. The arm 120 is vertically operated by and is pivoted about a pin 126 which is set in a block 129 which rides in a slot 130. The block 129 is set 15 at a fixed position in the slot 130 by a fastening device 131. The slot 130 is set in the wheel 127 which rotates on a shaft 128 driven by a suitable power source. The farther the block 129 is set from the shaft 128, the greater the stroke of the arm 120. Thus the intermittent feed of the 20 roller feeding means 7 can be varied and regulated as desired.

Referring more particularly now to the pawl and ratchet arrangement in Figure 7, the pawl referred to generally as 121 consists of an engaging rod 122 pressed by spring 123 into engagement with ratchet teeth 116. It is to be noted that the engaging surface of this rod at 124 is obliquely shaped so as to securely engage 25 ratchet teeth 116 when being moved downwardly and which will slide out of engagement with the ratchet teeth by reason of the surface and the spring action when moving upwardly.

Referring now more particularly to Figure 6, 30 a main shaft 155 is driven by power-driven pulley 156, the power being applied through a belt 154. Fixedly mounted upon and adapted to rotate with this power-driven shaft is a cam 158, which operates the trigger mechanism 75 through the roller 81 and rod 71, more specifically shown 35 in Figure 2 and described hereafter.

Also fixedly mounted upon this shaft is a sprocket wheel 110 with teeth 111 adapted to engage the chain 11 described hereinbefore. Fixedly mounted next on this shaft 155 and adapted 40 to rotate therewith is a cam 161. The cam 161 operates by its periphery to move in a vertical path the roller 162 mounted on the arm 163, which is pivoted at 164, thus vertically moving the rod 31, which operates the knife mechanism, 45 more particularly shown in Figures 2 and 4.

Mounted next on the power-driven shaft 155 and fixed thereto is the cam 166, which by the contour of its periphery actuates a movement in roller 59 mounted on the arm 58 which acts 50 through the pivot at 57 to actuate the pusher rod 52, shown more particularly in Figure 2.

Mounted next on the power-driven shaft 155 and fixed to rotate therewith is a sprocket wheel 170 with teeth 171 which engage chain 172, which chain runs over gear 173 which drives the roll 95, supplying the power for the conveying belts. Fixedly mounted next on the power-driven shaft 155 and adapted to rotate therewith is a cam 176, which moves, by its peripheral contour, roller 177 in a vertical path. Roller 177 is fixed 60 on the end of an arm 178 pivoted fixedly at 179, which arm moves upwardly against the action of the spring 181. The vertical movement of the roller 177 serves to move the arm 182, which moves the lever arrangement 183, causing the manipulating member 70 to move about the axis 184 in a path more clearly shown by Figures 8 to 11. The member 70 extends into two bifurcated 65 members 186 and 187 to allow the entry of the

trigger 15, as indicated in the Figures 8 to 11. This bifurcation is shown in plan in Figure 1.

I shall now describe the operation of my device. A roll of paper 4 is mounted upon the shaft 3 and 5 is fed between the rubber rolls 8 and 9, the upper roll 8 being yieldably pressed against roll 9 so that a firm grip upon the paper is established. Intermittent action of the feeder roll 7 is established by means of the pawl and ratchet arrangement shown more particularly in Figures 5 and 6. The 10 rotation of the rotating wheel 127 acts to move the arm 120 vertically, thus causing a rock up and down motion of the arm 118 through the pivot 119. On its downward path the pawl 121 engages the ratchet teeth 116 and moves it 15 through a predetermined path (see also Figure 7). On the upward path of arm 118 the pawl 121 slips by the ratchet teeth 116 with no movement of the wheel 115. It is to be seen, therefore, that by reason of the here-described mechanism 20 the rolls 8 and 9 operate periodically and intermittently to feed forth a certain length of the reinforcing paper 4 in the indicated path. The position of the block 129 in the slot 130 determines 25 the extent of the length of paper fed each time.

On emerging from the feeder rolls 8 and 9, the paper 4, which has an under-surface with an adhesive surface which acts to adhere on application of liquid, moves over the applicating roll 16, 30 which continuously moves in the direction indicated by the arrow thereon in Figure 2 through a bath of liquid 20, thus serving to continuously apply the necessary wetting liquid to this under-surface. Obviously the applicator roll 16 could 35 apply an adhesive to a plain paper reinforcing strip. The paper thus moves through the flanged rolls 23 and 24, which engage it only at its edges by reason of their spindle shape, as shown more clearly in Figure 1, so as not to mar the moistened adhesive under-surface of the paper. The upper 40 roll 24 is slidably mounted; its shaft 26 sliding in the slot 27 rests on the lower spindle roll 22 which is driven by the chain 17. Thus a constant drag on the intermittently advancing paper 4 is maintained. In a modified form of my invention the upper roll 24 could be solid surfaced 45 instead of having flanged ends since there is no adhesive surface on the upper side of the re-enforcing strip which side comes in contact with this roll 24. As the paper is fed forward, it passes 50 through the open knives 29 and 30 pivoted at 28, as is more particularly shown in Figure 4, to a position under the manipulating member 70 and over the bag which has been advanced to a proper 55 position against the lower knife blade 29 from the other end of the mechanism.

An ordinary paper bag 200 is shown in plan and side elevation in Figures 12 and 13. It is to be noted that the bottom of the bag 201 is folded 60 in a conventional manner about the lower portion of the bag. The purpose of this invention is to apply the reinforcing piece 202 to the bottom of that bag, thus making a solid bag structure with reinforcement at the point of greatest strain. 65 A bag with its bottom folded thereover as shown in Figure 13 is placed upon the platform 50 with the folded portion uppermost. When the bag is placed upon this platform, pusher rod 52 is in its position farthest back, indicated by dotted 70 lines. By suitable cam action acting through the roller 59 and arms 56 and 58, the pusher rod 52, which is firmly affixed at 55, is brought forward to the solid line position. In its path forward it 75 brings the bag 200 forward on the platform 50 so

that the folded bottom 201 comes to a stop under the manipulating member 70 and against the lower knife blade 29. When the bag has reached this position, the adhesive coated paper 4 is brought forward by reason of the related action of the chain 114 which intermittently drives the roll 8 and by reason of the action of the chain 17 which continuously drives the applicator roll 16 and the flanged roll 23. The paper 4 with its adhesive under-surface moistened from the bath 20 is brought to a position indicated in Figure 2 and there is positioned directly over the bottom of the bag 201 with the moistened adhesive surface 5 facing downward. At this point, by reason of the related cams shown in Figure 6, there is effected the action which is shown quite clearly in Figures 8 to 11. First the enlarged portion of the cam 161 comes in contact with and forces downwardly the roller 162, which is rigidly mounted on the arm 163 pivoted at 164. By its action through 32 the rod 31 is moved downwardly and the knife blade 30 comes in cutting contact with the lower knife blade 29, cutting off the advanced portion of this paper 4. This section 202 of moistened adhesive paper then drops to its proper position on the folded bottom of the bag 201, as shown in Figure 9.

There now follows a coacting movement of the manipulating member 70 and the trigger 75, shown more particularly in Figures 10 and 11. The manipulating member 70 rotating upon an axis 184 is extended in the lever 183, which is pivoted at the point 182'. The arm 182 to which this member 70 is attached is moved vertically by means of the roller 177, which rides upon the cam 176. The enlarged portion 175 of the cam 176 acts, as is shown in Figure 3, to hold the member 70 in its normal position shown in Figures 2 and 3.

When the member 177 rides upon the lower portion of the cam 174, the manipulating member 70 is moved in the manner shown in Figures 10 and 11. At the same time that this member 70 is so moved, the trigger 75 is actuated through the rod 77 terminating in the roller 81, which rides on the cam 158. When the enlarged surface 159 of this cam 158 contacts with the roller 81, the trigger 75 is forced down through the bifurcated portions 186 and 187 of the manipulating member 70, which has by its action shown in Figures 10 and 11 both established a firmer contact between the reinforcing piece 202 and the bottom of the bag 201 and moved the bottom of the bag at an angle from its original position with respect to the remainder of the bag, as shown in Figures 10 and 11. The trigger 75 now comes down and contacts the rear edge 203 of the bottom of the bag 201 and throws it forward so that the forward edge of the bottom of the bag is forced between the travelling belts 87 and 88, as shown more clearly in Figure 11. These belts 87 and 88 draw the bottom of the bag 201 and the bag 200 itself from the platform 50 to between their engaging surfaces, wherein the reinforcing section 202 is firmly pressed onto the bottom of the bag 201 and the entire bag 200 carried forward between these belts 87 and 88 and discharged into the receptacle 112.

It is to be noted that, as shown in Figure 6, upon a single driven shaft 155 there is mounted the operating cams and the driving pulleys; the cams are so placed so that the various operations indicated previously will coact in the desired and indicated manner. The positions of these cams and their surfaces with respect to each other is

indicated in Figures 2 and 6. The operation of all mechanisms of this machine are initiated from a set of operating means which are in fixed synchronous relation to each other and virtually set on a single shaft.

By means of the apparatus and method above-described, I have found it possible to apply reinforcing patches to bags quickly, economically and efficiently.

Various changes and modifications can be made in the apparatus shown by one skilled in the art without departing from the invention here disclosed. I intend to limit my invention only as set out in my claims.

I claim:

1. In a machine for applying re-enforcing patches to bags, in combination, a platform; means for positioning the bag with its folded bottom uppermost on the platform; means for feeding a strip of material to a position over the bottom of said bag; means for applying a patch from said strip of material to the bottom of the bag; means for turning the bottom of the bag to an angle with respect to the remainder of the bag and means for advancing the bag adapted to coat with the turned bottom of the bag.

2. In a machine for applying re-enforcing patches to bags, in combination, a platform; means for positioning the bag upon said platform with its folded bottom uppermost; means for feeding intermittently a strip of material forward to a position over the bottom of the bag; means for continuously drawing said strip of material forward; means for applying a patch from said strip of re-enforcing material to the bottom of the bag; means for turning the bottom of the bag and pressing the strip thereon and means for advancing the bag from the platform.

3. In a machine for applying re-enforcing patches to bags, in combination, a platform; means adapted to periodically engage a bag and move it forward to position it with its folded bottom portion uppermost on said platform; means for advancing a strip of material to a position over the bottom of said bag; means for applying a patch from said strip of material to the bottom of the bag; means for turning the bottom of the bag to an angle with respect to the remainder of the bag; and means for advancing the bag from the platform.

4. In a machine for applying re-enforcing patches to bags, in combination, a platform; means adapted to periodically engage and move forward said paper bag to a position on said platform with its folded bottom uppermost; means for intermittently feeding a strip of material to a position over said bottom of the bag; means for continuously drawing said strip forward; means for severing a portion of said strip to provide a patch upon the bottom of said bag; means for turning the bottom of said bag to an angle with respect to the remainder of the bag; and means for advancing the bag from the platform.

5. In a machine for applying re-enforcing patches to bags, in combination, a platform; a pusher member adapted to engage and bring forward a bag with its folded bottom uppermost to a certain position upon the platform; means for causing the pusher member to move back and forth at predetermined intervals; variable means for intermittently feeding a strip of material comprising, a roll yieldably mounted in engagement with a similar roll; means for inducing adhesion on one surface of said strip of material;

15
